UNITED STATES PATENT OFFICE.

WILLIAM H. WHERRY, OF CLEVELAND, OHIO, ASSIGNOR TO THE FOREST CITY ELECTRIC COMPANY, OF CLEVELAND, OHIO, A CORPORATION OF OHIO.

FORMER FOR RAIL-BONDS.

SPECIFICATION forming part of Letters Patent No. 766,207, dated August 2, 1904.

Application filed October 12, 1903. Serial No. 176,644. (No model.)

To all whom it may concern:

Be it known that I, WILLIAM H. WHERRY, a citizen of the United States, and a resident of Cleveland, county of Cuyahoga, and State of Ohio, have invented a new and useful Improvement in Formers for Rail-Bonds, of which the following is a specification, the principle of the invention being herein explained and the best mode in which I have contemplated applying that principle, so as to distinguish it from other inventions.

My invention relates to mechanism for forming rail-bonds, and particularly to such mechanism that is used for straightening and shaping the bonds after they have been manufactured and finished off.

Said invention consists of means hereinafter fully described, and specifically set forth in the claims.

The annexed drawings and the following description set forth in detail certain mechanism embodying the invention, such disclosed means constituting but one of various mechanical forms in which the principle of the invention may be used.

In said annexed drawings, Figure I represents a plan view of the mechanism embodying my invention, showing a bond in position before straightening and in dotted lines in position after straightening. Fig. II is a central longitudinal vertical section of said mechanism; and Fig. III is a transverse section through the plane indicated by the line 3-3, Fig. II, showing parts in elevation. Fig. IV is a plan view of a straightened bond, and Fig. V a plan view of said bond after it has been shaped into the desired form.

Upon a table A is firmly fastened by casting or any other suitable means a strong lug a' of substantially the same width as the space between the sides of the bond which is to be formed. In the table and in longitudinal alignment with said lug a' is a groove or slide-

way a of substantially the same width as that of the lug and running from approximately 45 the center of the table to the front end thereof. Carried upon the end of the piston b of a cylinder B and located in said slideway a is another lug, b' , of substantially the same width as that of lug a' and extending up out of the 50 slideway a to a height substantially equal to that of lug a' .

Laterally of the table A are two other cylinders, C and D, one on either side of the table, provided with pistons c and d , respectively, upon the outer ends of which are formed headed pieces c' and d' , respectively, the lower face of said pieces lying in the same horizontal plane as the top of the table A, so that they may slide freely upon the same. Longitudinally abutting the pieces c' and d' and securely bolted thereto are two other pieces, c'' and d'' , respectively, preferably rectangular in shape, and cast integral with these latter pieces or fastened to them by any other suitable means are projections c^3 and d^3 , respectively, for indenting the bond, as will be hereinafter more fully described. Intermediate of the lugs a' and b' two projecting lugs a^2 a^2 are fastened to the table A, which act as shapers 70 for the bond when it is indented by the projections c^3 and d^3 , the shapers and projections illustrated in Fig. I being designed to shape the bond into substantially the form shown in Fig. V. The pieces c^2 and d^2 may be fastened 75 to the pieces c' and d' , respectively, at any desired points, and any construction and size of pieces c' , c^2 , d' , and d^2 , projections c^3 and d^3 , and shapers a^2 may be utilized, so that the strands e' of the bond E may be indented 80 into any shape and at any point desired and the bond shaped into the desired form, only one form and size of said pieces, projections, and shapers being illustrated in the drawings.

Referring to the bond itself, it is shown as 85 comprising the two heads or terminals e and

the two sets of connecting-strands $e' e'$. These sets of connecting-strands are made of metal, preferably copper, and each set comprises several strands or conductors, so as to afford a 5 large conducting-surface for the current. Said bonds are designed to furnish an electrical connection between two abutting rails, and in order that any possible play between the ends of the rails may be provided for, which 10 may be needed by reason of the contraction and expansion of the rails or by reason of their becoming loosened in various ways, the strands or conductors are bent or indented, as shown in Fig. V.

15 In operating the above-described mechanism a terminal e of a bond E is laid over the lug a' and the other terminal over the lug b' , as shown in full lines in Fig. I. Compressed air from any suitable source (not shown) is 20 forced into the cylinder B through the connection B' by means of a valve operated by a foot-lever F, and the piston b is driven forward, carrying with it the lug b' , which straightens the strands e' of the bond E, and thus carries 25 the bond into the straightened position (shown in dotted lines in Fig. I) and gives the bond the shape illustrated in Fig. IV. The foot-lever F is then relieved, thus shutting off the compressed air from the cylinder B, whereupon 30 the piston b, and with it the lug b' , is forced back into the position shown in full lines in Fig. I by the compressed air in the space between the piston and the front head of the cylinder, which pressure is maintained 35 by small perforations b^2 in the piston, whereby communication is afforded for the comparatively slow ingress of air into the front head of the cylinder from the rear head. After the strands of the bond have been thus straightened 40 compressed air is forced into the cylinders C and D through the connections C' and D' by means of valves controlled by the hand-lever G, and against the bond-strands the projections c^3 and d^3 are thus forced, forming the 45 bond into the desired form, as illustrated in Fig. V, by means of the two projecting lugs $a^2 a^2$. The shaped bond is then removed, another inserted over the lugs a' and b' , and the process repeated, pistons c and d having means 50 while been withdrawn by means of compressed air forced into the cylinders C and D through the connections C^2 and D^2 by reversing the hand-lever G.

By the above-described means the bonds are 55 straightened and formed into the desired shape very satisfactorily, and as a result of the variable stroke attainable by air-pressure the bonds are not required to be of a constant length, as they are when a machine of positive 60 stroke is utilized for this purpose, but may vary in length as much as is desired.

Other modes of applying the principle of my invention may be employed instead of the

one explained, change being made as regards the mechanism herein disclosed, provided the 65 means stated by any one of the following claims or the equivalent of such stated means be employed.

I therefore particularly point out and distinctly claim as my invention—

1. In a former for rail-bonds, the combination of lugs for holding the bond, means for laterally indenting the bond, and lugs intermediate of the two sets of bond-strands for keeping portions of said two sets of strands 75 separate, when the bond is indented.

2. In a former for rail-bonds, the combination of lugs for holding the bond, oppositely-disposed projections for laterally indenting the bond intermediate of said holding-lugs, 80 and lugs intermediate of said holding-lugs and located between the two sets of bond-strands for shaping the bond, when it is indented.

3. In a former for rail-bonds, the combination of lugs for holding the bond, reciprocatory means for straightening the bond, oppositely-disposed projections for laterally indenting the bond, and lugs intermediate of 85 said holding-lugs for shaping the bond, when 90 it is indented.

4. In a former for rail-bonds, the combination of a stationary lug and a movable lug for holding the bond, oppositely-disposed projections for laterally indenting the bond intermediate of said holding-lugs, and lugs intermediate of 95 said holding-lugs for keeping portions of the two sets of bond-strands separate, when the bond is indented.

5. In a former for rail-bonds, the combination of a stationary lug and a movable lug for holding the bond, lugs intermediate of 100 said holding-lugs for shaping the bond, and oppositely-disposed projections for laterally indenting the bond intermediate of 105 said shaping-lugs.

6. In a former for rail-bonds, the combination of a support, lugs for holding the bond, reciprocatory means for straightening the bond, one of said holding-lugs being stationary and located upon said support, and another of said holding-lugs being movable and carried by said straightening means, and oppositely-disposed projections for laterally indenting the bond intermediate of 110 said lugs. 115

7. In a former for rail-bonds, the combination of lugs for holding the bond, reciprocatory means for straightening the bond, oppositely-disposed projections for laterally indenting the bond, and reciprocatory means 120 adapted to operate said projections.

8. In a former for rail-bonds, the combination of lugs for holding the bond, means for straightening the bond, means providing communication between the rear and front of said 125 straightening means for creating a back pres-

sure to withdraw said straightening means, and means for laterally indenting the bond.

9. In a former for rail-bonds, the combination of lugs for holding the bond, means for straightening the bond, perforations connecting the rear and front of said straightening means for creating a back pressure to withdraw said straightening means, means for laterally indenting the bond, and reciprocatory

means adapted to operate said indenting means.

Signed by me this 30th day of September, 1903.

WILLIAM H. WHERRY.
